Primary Examiner — Steven J Czyz(74) *Attorney, Agent, or Firm* — Myers Wolin, LLC(57) **CLAIM**

The ornamental design for a stethoscope holder, as shown and described.

DESCRIPTION

FIG. 1 is a perspective view of one embodiment of a stethoscope holder showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view in a use condition.

The dotted lines represent portions of the stethoscope holder that form no part of the claimed design.
